UNITED STATES PATENT OFFICE.

ALBION L. WARNER, OF NEW YORK, N. Y., ASSIGNOR TO CHARLES LYON BURSELL, OF RAHWAY, NEW JERSEY.

FOLDING TABLE.

Application filed December 5, 1924, Serial No. 754,041. Renewed June 24, 1927.

This invention relates to a table top formed of two normally disconnected sections, one of which is adapted to fold down within the table top frame and the other to overlie the frame, both of which sections are adapted when spread out to make a table substantially twice the area of such covering section.

The object of the invention is to securely 10 guide the covering section so that it is constrained to move on the plane of the upper surface of the frame and to guide the folding or disappearing section so that it does not skew or move obliquely to the other section or the frame and will hold the parts 15 solidly in their opened position.

Figure 1 is a front elevation partly in vertical section on the line, 1-1, of Figure 2.

Fig. 2 is a cross section at about the plane of the line, 2-2, of Fig. 1 showing the table in its folded position and

Fig. 3 is a similar view showing the table in its opened position, one of the leaves in this view being broken away.

The frame for supporting the table top is shown composed of front and back longitudinal members, 5 and 6, and end members, 7. This frame is supported in some convenient 30 or well known manner, shown in the form of legs, 8. There are two leaf sections, 10 and 11. For convenience the section, 10, may be referred to as the cover section and the leaf, 11, owing to the fact that it is constructed 35 and adapted for depression and housing within the frame and below the cover section, 10, as the folding or disappearing section. The cover section, 10, carries guide members, 12, engaging suitable guiding slots, 13, formed in the ends, 7, of the frame to hold it firmly down upon the upper surface 40 of the frame so that it will move on the plane of such upper surface. There is also provided at each end a strip, 14, of such length and so positioned that its ends will 45 strike the frame members, 5 and 6, when in its closed position and its opened position, thereby, limiting its shifting movements of opening and closing. These strips also have 50 sufficient tightness of fit to engage the surface of the frame ends, 7, to prevent skewing of the cover, 10.

The folding or disappearing leaf or table top section, 11, is preferably narrower than 55 the covering or sliding section, 10, and of

sufficient width to drop between the front and back framing members, 5 and 6. At the back of the meeting edge, this leaf, 11, carries at each of its ends a guide preferably formed of flat metal, 15, which are adapted to run in slots, 16, formed in the frame ends, 7. The slot has an upwardly directed somewhat obliquely disposed portion, 161, ending in the slot, 13. A steadyng member or device is associated with the leaf, 11, to prevent it skewing in its various movements. This member in the present instance comprises a rigid linkage consisting of two boards, 17 and 18, disposed longitudinally of the table frame and pivoted together preferably by means of a plurality of hinges, 19. The board, 17, is shown pivoted to the frame, 20, secured to such board and the lower edge 70 of the front frame member, 15. The board, 18, is shown similarly connected to the leaf, 11, by means of hinges, 21, secured to a longitudinal cleat, 22, fastened at an appropriate position to the bottom face of the leaf. A stop, 23, in the form of a wedged shape 75 cleat is fastened to the under side of the leaf, 11, to engage behind the front member, 5, for preventing the forward movement of the leaf while resting on the frame member. Some suitable means, as for instance, a strap, 24, is provided for convenience in 80 raising and folding up the leaf, 11.

The operation of the device when constructed as illustrated is as follows:

Assuming the parts to be in the position 90 illustrated in Figures 1 and 2, the operator standing at the front or right hand side of the table in its Figures 2 and 3 position will push the cover member, 10, back until the rear ends of the strips, 14, engage the rear framing member, 6. The operator then by means of the handle, 24, raises the front and exposed edge of the leaf, 11, above the top edge of the frame, 5, then draws the leaf forward, the guide, 15, traversing the 95 slot, 16, until further forward movement is prevented by engagement between the guide and the face, 162, of the slot, during this movement the operator raising the stop, 23, above the upper edge of frame member, 5. The operator then pushes the leaf backwardly and partly subconsciously and partly 100 through the natural working of the parts brings the leaf into a horizontal position passing the guide, 15, through the slot por- 105

tion, 161, until the guide engages the top end or surface of the slot which is so positioned as to bring the leaf, 11, into the plane of the leaf or cover, 10. During this operation the leaf, 11, is pushed backwardly a sufficient distance to cause the guide, 15, to occupy a portion of the slot, 13, which is so located and proportioned as to prevent the back end of this leaf moving either upwardly or downwardly. The stop, 23, is then in position to prevent the accidental forward movement of either or both of the leaves. When it is desired to again close the top the operator raises the front edge of the leaf, 11, to release the catch, 23, and draws the leaf forward a sufficient distance for the guide, 15, to move out of the slot, 13, and into the slot portion, 161, the leaf is then pushed backwardly causing the guide to traverse the sections, 161 and 16 of the slot until the leaf is fully housed within the frame, whereupon the cover section, 10, is moved forwardly until the front ends of the strips, 14, engage the front frame member, 5. Finishing pieces, 25, are shown carried by the end frame member, 7, for abutting the edges of the leaf, 10, when this is in its closed or covering position and for abutting the meeting edges of both leaves when these are in the open position.

During the various movements of opening and closing the leaf, 11, the steadyng member or rigid links, 17, and 18, offer no resistance to the forward and backward and upward and downward movements and combinations of these. They do, however, prevent any skewing movement. This assures that the guides, 15, shall remain in their proper position and that the leaves shall

neatly come together when opened out and 40 that the leaf, 11, shall descend and be neatly and expeditiously housed within the frame.

While I have shown in the drawings but one embodiment of my invention it will be apparent that changes may be made within 45 the scope of the claims without departing from the spirit of my invention.

Having described my invention I claim and desire to secure by Letters Patent:

1. In a folding table, the combination 50 with a frame, of a leaf adapted to be housed in the space within the frame and to be raised therefrom and rest upon the frame for forming a part of a table top, a pair of rigid links pivoted together and to the leaf and frame for preventing skewing of the leaf, and a cover leaf shiftable across the frame and adapted when in closed position to cover the frame and the housed leaf, and when in open position to expose a portion 60 of such space and to cooperate with the said leaf in forming a table top.

2. In a folding table, the combination 65 with a frame, of a leaf adapted to be housed in the space within the frame and to be raised therefrom and rest upon the frame for forming a part of a table top, a pair of boards extending longitudinally of the leaf and pivoted together and to the leaf and frame, and a cover leaf shiftable across the 70 frame and adapted when in closed position to cover the frame and the housed leaf, and when in open position to expose a portion of such space and to cooperate with the said leaf in forming a table top.

Signed at New York, New York, this 2nd day of December, 1924.

ALBION L. WARNER.
